HANDLE FOR CULINARY UTENSIL

Clifford R. Keeslar, Springfield, Va., assignor to Sears, Roebuck and Co., Chicago, Ill., a corporation of New York

Filed May 9, 1966, Ser. No. 2,219

Term of patent 7 years

(Cl. D44—29)

FIG. 1 is a perspective view of a handle for a culinary utensil showing my new design;

FIG. 2 is a perspective view taken from another angle;

FIG. 3 is an enlarged scale side elevational view;

FIG. 4 is a top plan view;

FIG. 5 is a bottom plan view; and

FIGS. 6, 7 and 8 are sectional views taken respectively on lines 6—6, 7—7 and 8—8 of FIG. 3.

The broken line showings of a ladle in FIG. 1 and portions thereof in FIGS. 2 and 3 are for illustrative purposes only.

I claim:

The ornamental design for a handle for culinary utensil, as shown and described.
